UNITED STATES PATENT OFFICE.

WILLIAM C. SHAFFER AND ARTHUR M. WHITE, OF PHILADELPHIA, PENNSYLVANIA, ASSIGNORS TO THE RAILROAD SAFETY LOCK AND SIGNAL COMPANY, OF NEW JERSEY.

MEANS FOR AUTOMATICALLY STOPPING TRAINS AND SIGNALING.

SPECIFICATION forming part of Letters Patent No. 269,235, dated December 19, 1882.

Application filed September 1, 1882. (No model.)

To all whom it may concern:

Be it known that we, WILLIAM CASS SHAFFER and ARTHUR M. WHITE, both citizens of the United States, residing in the city and county of Philadelphia, and State of Pennsylvania, have invented a new and useful Improvement in Means for Automatically Stopping Trains and Signaling, which improvement is fully set forth in the following specification and accompanying drawings, in which—

Fig. 1 is a view of the apparatus embodying our invention in position on a locomotive-engine. Fig. 2 is a side elevation of a portion thereof enlarged. Fig. 3 is a side elevation of the valve thereof and connected mechanism enlarged. Fig. 4 is a top view thereof. Fig. 5 is a transverse vertical section of the valve, Fig. 3, in line *x x*, Fig. 6, and a vertical section of a connected cylinder. Fig. 6 is a longitudinal vertical section of the valve in line *y y*, Fig. 4.

Similar letters of reference indicate corresponding parts in the several figures.

Our invention consists of a locomotive-engine having a valve independent of the usual valve or valves, and connected mechanism, whereby in the event of danger along the road said independent valve is automatically opened and said mechanism thereby operated to shut off the steam from the cylinders, apply the brakes, and stop the train, and sound the alarm.

It also consists of a leg or equivalent device attached to an axle-box of the engine, having its lower end carried at an invariable distance from the top of the rails of a railroad, so as to strike a projection or shoe along the line of the road, and thereby operate a valve on the engine for stopping the latter, and signaling in the event of danger.

It also consists in constructing the aforesaid leg in such manner that it is rendered inoperative when the engine is backed.

Referring to the drawings, A represents a box of one of the axles of a locomotive-engine, and B represents a valve, the stem whereof carries two heads, *a a'*, and the shell or body has two seats, *b b'*, for said heads *a a'*, said valve being in communication with the boiler

of the engine and secured thereto independent of the usual valve or valves of the engine.

Communicating with the body of the valve is a pipe, C, which, by means of a pipe, D, communicates with a cylinder, E, the latter being secured to the cab or boiler of the engine, and having within it a piston, F, whose stem F' has attached to it chains, levers, rods, &c., G, which are connected with the levers *A' A''*, respectively, of the throttle-valve and whistle.

To the shell or body of the valve is pivoted an elbow-lever, H, one limb of which has pivoted to it an arm, J, the end of which opposite to its pivotal connection with the lever H is attached to an upright leg, K, which, pivoted to the box A, is adapted to be engaged by a projection, foot, or shoe, L, the latter being located along the line of the railroad and supported on sleepers, ties, or other proper portion of the road-bed thereof.

Against the back of the leg K bears a spring, M, which is attached to the axle-box A or the frame of the engine, and serves to prevent abrupt motion of the leg when it strikes the projection L, and restore it to its normal position.

N represents a spring which is attached to the body of the valve B, and formed at top with a bent end, c, and adjacent thereto a curvature or depression, d, into which drops the upper end of the elbow-lever, H, said spring being furthermore arranged to bear against the stem B' of the valve B when the elbow-lever H is operated, the normal position of parts being shown in Fig. 3.

Formed with or secured to the body of the valve is a branch, P, which has an outlet, f, and a spring-valve, P', therefor, and to said branch is screwed or coupled a pipe, Q, communicating with the air, steam, vacuum, or other brake mechanism of the engine or train, said valve being located beneath the upper limb of the elbow-lever H, so that when said lever is in its normal position and engaged by the depression d of the spring N, the upper limb of the lever bears against the valve P' and holds it on its seat, thus closing the opening or outlet f. When the elbow-lever is operated it no longer controls the valve P',

and the latter is permitted to open, thus uncovering the outlet *f*, whereby the air, &c., of the pipe *Q* may discharge through or be admitted to said outlet for the purpose of operating the brakes.

R represents a drip or discharge pipe, which communicates with the body of the valve *B* in the portion containing the head *a* of said valve, whereby, when the head *a'* is on its seat *b'* and the head *a* removed from its seat *b*, the water of condensation of steam is permitted to escape or exhaust through said pipe *R*.

To the elbow-lever *H* is pivoted an arm or rod, *S*, whose upper end is within convenient reach of the engineer or other person on the engine, so that said lever may be reset and the connected parts assume their normal positions.

The operation is as follows: The shoe *L* may be automatically held immovable by means such as are shown in the Letters Patent No. 250,173, granted to Wm. C. Shaffer on the 29th day of November, 1881, or otherwise set automatically or by hand, such operation of the shoe being occasioned where there are accidents, misplaced switches, open draws, &c., along the road, and it is essential to stop the train. As soon as the leg *K* strikes the shoe, the former is carried rearward, thus drawing with it the arm *J* and turning the elbow-lever, whose upper limb is released of the depression *d* of the spring *N*, and raised so as to rest on the top bend, *c*. The spring, heretofore expanded and now uncontrolled by the elbow-lever, advances against the stem *B'* of the valve *B*, thus moving the head *a'* from its seat *b'* and closing the head *a* on its seat *b*. Steam or hot water then enters the body of the valve and passes through the pipes *C D* to the cylinder *E*, whereby the piston *F* is depressed or advanced, and the connections *G* are moved by said piston, the effect whereof is to operate the throttle-valve and shut off the steam to the cylinders of the engine, and likewise move the whistle-lever, thus causing the whistle to blow. Simultaneously therewith the valve *P'*, relieved of the elbow-lever, is permitted to rise and the opening *f* is uncovered, whereby air, &c., may be discharged from or admitted to the pipe *Q*, and the brakes are operated. By depressing the lever or arm *S* the elbow-lever, which has rested on the end *c* of the spring *N*, forces back said spring until it drops into the depression *d* thereof, thus resetting said lever. The valve-stem is no longer controlled by the spring, so that the pressure of steam from the boiler acts on the head *a'* and closes it on its seat *b'*, thus shutting off steam to the valve. The head *a* leaves its seat *b*, and the condensed steam or hot water in the body of the valve escapes through the pipe *R*, as has already been stated. The pull on the throttle-valve is much more gradual when my valve *B* is employed than it would be if connection were made solely through rods and levers. Hence there is no danger of jerking the handle of the throttle-valve violently from the

hand of the engineer if he should happen to have hold of it.

The arm *J* is longitudinally slotted at the end connected with the leg *K*, and receives a stud or pin, which is fixed to the leg below the pivot of the leg, so that when the engine is backing, should the leg strike the shoe, said stud or pin plays in the slot of the arm without imparting motion to the arm and connected parts of the device. The leg *K* is pivoted to a box, *A*, or another box fitted to an axle of the engine, so that its lower end always stands or is carried at an invariable distance from the top of the rails of the road, whereby its action is positive, as it reaches the different shoes along the road, and the reliable operation of the valve *B* is thus occasioned.

Having thus described our invention, what we claim as new, and desire to secure by Letters Patent, is—

1. A valve attached to a locomotive-engine and communicating with the steam-supply thereof, in combination with the usual valve or valves and means, substantially as described, whereby in the event of danger along the railroad steam is automatically shut off from the cylinder of the steam-engine, the brakes are applied, the alarm is sounded, and the engine or train is stopped, substantially as set forth.

2. A valve attached to a locomotive-engine, in combination with a cylinder having a piston, with which are connected the throttle-valve and whistle-lever and the brake mechanism, said valve being in communication with the steam-supply and said cylinder, whereby the valve may be operated by means located along the road, and the piston thereby actuated, thus automatically shutting off steam and applying the brakes and stopping the engine or train, substantially as and for the purpose set forth.

3. A valve in communication with the boiler of a locomotive-engine and an attachment to said engine adapted to be engaged by a projection or shoe along a railroad, in combination with a cylinder communicating with the aforesigned valve, and having a piston which is connected with the whistle-lever and brake-operating mechanism, whereby in the event of danger said piston is operated, thus automatically operating the whistle and stopping the train, substantially as and for the purpose set forth.

4. A valve in communication with the boiler of a locomotive-engine and an attachment to said engine adapted to be engaged by a projection or shoe along a railroad, in combination with a pipe communicating with the brake mechanism, and having a valve independent of the usual valves of the engine, whereby in the event of danger said valve is opened, thus automatically applying the brakes, substantially as and for the purpose set forth.

5. In a device for automatically stopping a locomotive-engine or train, a leg attached to the axle-box or box on the axle of the engine, substantially as described, whereby it is carried an unvarying distance from the top of the

rail of the road, and adapted to engage positively with an operating projection or shoe along the road, substantially as and for the purpose set forth.

5 6. The leg K, in combination with the arm J, having a longitudinally-extending slot for the connecting-stud of said leg, whereby said leg is rendered inoperative when the engine is backed, substantially as and for the purpose 10 set forth.

7. The valve and its stem with the two seats and heads, in combination with the elbow-lever and the spring formed with a depression to receive the end of said lever, substantially as and 15 for the purpose set forth.

8. The valve B, in combination with the

brake-pipe Q, having a valve, P', and the overhanging lever H, substantially as and for the purpose set forth.

9. The valve B and its stem with the two 20 seats and heads, in combination with the drip or exhaust pipe R, substantially as and for the purpose set forth.

10. The valve B, in combination with elbow-lever H, spring N, and resetting-arm S, sub- 25 substantially as and for the purpose set forth.
